United States Patent Office

Des. 191,317
Patented Sept. 12, 1961

191,317

STAND FOR FLOWER POTS

August Rohrmuller, 198—40 32nd Ave., Bayside, N.Y.

Filed June 20, 1960, Ser. No. 61,045

Term of patent 7 years

(Cl. D35—3)

Fig. 2.

Fig. 1.

Fig. 4

Fig. 3

FIG. 1 is a front perspective view of a stand for flower pots embodying my new design.

FIG. 2 is a side elevational view taken from the right of FIGURE 1.

FIG. 3 is a top plan view thereof.

FIG. 4 is a fragmentary bottom plan view of one of the shelves thereof.

I claim:

The ornamental design for a stand for flower pots, as shown.
